FLASHLIGHT

William M. Lennan, Los Angeles, Calif.

Application March 11, 1957, Serial No. 645,313

9 Claims. (Cl. 240—11.3)

The present invention relates generally to flashlights and more particularly to an improved flashlight that is adapted for safe use under certain hazardous conditions.

Under many circumstances flashlights must be used in potentially dangerous situations. For example, they may be employed to inspect the interiors of tanks that contain combustible or explosive atmospheres. If the light is inadvertently dropped so that its lens or bulb is broken, fire or explosion may result due to arcing across the bulb filaments. Similarly as a result of dropping the flashlight a spark may be struck by its impact on the tank. Such a spark may also be sufficient to ignite an explosive atmosphere. Recognizing this hazard, underwriters require that flashlights used in such situations be adapted to avoid any possibility of arcing or sparking resulting from dropping the light or other such accident.

An object of my invention is to provide a flashlight that has means to automatically electrically disconnect its bulb from its batteries in the event of breakage of its lens or bulb. By these means any possibility of the bulb filaments arcing or continuing to burn in an explosive atmosphere is eliminated.

Another object of my invention is to provide a flashlight of this character that is provided with a resilient outer cover that will absorb the impact of any fall of the light and therefore will not cause a spark when struck against a metal surface. Additionally, this outer cover is adapted to support the lens of the light in such a way as to define a fluid sealed housing that prevents any entrance of a potentially explosive atmosphere into contact with the hot light bulb.

A still further object of my invention is to provide a novel form of bulb mounting means for a flashlight that is of simplified, inexpensive construction. This mounting means is adapted to receive bulbs with threaded or unthreaded bases and in either case will automatically eject the bulb in the event of fracture of the flashlight lens or bulb.

The invention also has for an object the provision of a safety flashlight of this character that is adapted to carry a spare bulb in a protected position wherein it will not be broken even if the flashlight is dropped.

These and other objects and advantages of the invention will be apparent from the following description of a presently preferred embodiment thereof and from the drawing annexed hereto in which:

Figure 1 is a longitudinal section through a flashlight embodying my invention, and showing the normal position of a flashlight bulb in the bulb mounting means;

Figure 2 is a partial longitudinal section on an enlarged scale similar to Figure 1 showing the switch closed and a broken bulb ejected from electrical connection with the batteries of the flashlight; and

Figure 3 is a transverse sectional view on an enlarged scale taken along the line 3—3 of Figure 1, and showing details of the bulb mounting means and flashlight switch.

Referring now to the drawing for the general arrangement of the invention my improved flashlight is desig-

nated generally by the reference numeral 10. As is shown in Figure 1, the flashlight 10 includes tubular outer casing 11 which is made of rubber, neoprene or other similar elastomer having a closed end and an open end which carries a lens 12. The outer casing 11 and lens 12 together define a fluid-sealed housing in which an inner shell 13 is removably disposed that is adapted to support a plurality of replaceable batteries 14 between a base spring 15 and bulb socket 16. A bulb 17 is seated in socket 16 by means of a lens spring 18 that normally maintains bulb 17 in electrical connection with resiliently mounted contact means designated generally at 19. The inner shell 13 also carries switch means 20 operable from the outside of casing 11 by means of which the light may be turned on and off.

Specifically, the inner shell 13 is of substantially semi-cylindrical configuration and is preferably made of a metal such as steel. In Figure 1, I have shown my invention as embodied in a three cell flashlight but it will be understood that the inner shell 13 can be adapted to accommodate any number of cells. As is shown by the dotted outline in Figure 1, the rear portion 21 of the shell 13 is of slightly greater than semi-cylindrical configuration, while the forward portion 22 of shell 13 is slightly less than semi-cylindrical in configuration. The forward portion 22 thus defines a ready entrance for the introduction of batteries 14 into the shell 13 while the rear portion 21 is adapted to prevent any lateral displacement of batteries 14 from the shell 13.

The rear end of shell 13 is formed with an inwardly turned cup-like flange 23. Seated on diametrically opposite portions of the flange 23 is a spare bulb holder 24 that includes a pair of resilient clips 25 between which the stem of a spare bulb 17a is frictionally held. The base spring 15 is compressed between the rear battery 14 and the holder 24 and flange 23 to retain the holder in place as well as to electrically connect batteries 14 to case 13.

Rigidly affixed to the front end of the shell 13 is a generally conically shaped reflector cup 26 concentrically aligned with the shell 13 with its reduced rear end formed with a radially inwardly turned flange 27. The opening defined by the flange 27 is adapted to slidably receive a cylindrical crown 28 which is formed on the forward end of the socket 16. The cup flange 27 is adapted to seat an annular socket keeper 29 made of a resiliently deformable material such as Phosphor bronze formed with a plurality of radially inwardly inclined fingers 30 which normally define an aperture of less diameter than the socket crown 28. After the crown 28 of socket 16 is placed in position through the opening defined by the cup flange 27, the keeper 29 is pressed downwardly thereover and seated in place on the flange 27. This seating of keeper 29 results in deformation of the fingers 30 to the positions shown in Figures 1 and 2 wherein the fingers 30 have yielded to permit insertion of crown 28 therethrough. When keeper 29 is fully seated on flange 27, socket 16 is rigidly held in place between said keeper and the shoulder defined between crown 28 and the base portion 31 of the socket 16. Any tendency towards displacement of socket 16 is resisted by the engagement of fingers 30 with the socket crown 28.

Socket 16 is especially adapted for use with a bulb 17 of the type shown in the drawings. However, as will presently appear the socket can also be used with the ordinary type of flashlight bulb which includes a threaded base. The bulb 17 shown in the drawings has a smooth cylindrical base 32 which constitutes one of the terminals thereof. It will be observed that the rear end of the bulb base 32 is slightly rolled inwardly as is indicated generally by the reference numeral 33. Bulb 17 also includes a rearwardly protruding centrally disposed ter-

5
minal 34 which is insulated from cylindrical base 32. The terminals 32 and 34 are electrically connected by a filament 35 which is encased in a bulb envelope 36. The first terminal or base 32 of the bulb at its junction with the envelope 36 is formed with an outwardly extending annular flange 37.

The socket 16 is formed with an axial bore 38 extending therethrough which is adapted to loosely receive the bulb base 32 therein. The forward end of socket 16 has a spot face designated at 39 formed concentrically with bore 38 which is adapted to seat the bulb flange 37. As is shown in Figure 1, the lens spring 18 is adapted to engage the bulb envelope 36 at one end thereof, the other end of spring 18 being embedded in the lens 12 which is preferably made of a clear plastic material, such as that commercially available under the name "Lucite." This arrangement serves to keep the bulb 17 firmly but removably seated in the socket 16. The cup 26 rigidly mounts a concentrically aligned polished reflector 40 and as will be observed in Figure 1 when the bulb 17 is seated in socket 16 by the aforescribed means it is correctly disposed relatively to reflector 40.

A screw type flashlight bulb can also be used with the bulb mounting means just described. This type of bulb does not have any base flange for seating engagement with the socket spot-face 39 but can nevertheless be firmly held in place between the opposed lens spring 18 and resilient contact means 19, presently to be described.

Contact means 19 includes a battery contact spring 41 formed of a substantially rectangular piece of a conductive material having a finger 44 formed as a sideward continuation thereof. The spring 41 is fastened to the rear face of socket 16 by means of rivets 45 or the like (Fig. 3) with the finger 44 folded forwardly thereover (Fig. 2) to be disposed in a channel 43 that extends radially outwardly from socket bore 38 towards switch means 20. A rearwardly protruding dimple 46 on spring 41 contacts the center terminal of the adjacent battery 14. Referring to Figure 1, it will be seen that when bulb 17 is seated in socket 16 that its center terminal 34 makes contact with the finger 44 of spring 41 and also depresses said finger. The bulb 17 is thus electrically connected to batteries 14 and at the same time is subject to the biasing action of the depressed resilient finger 44.

The circuit through bulb 17 is completed by an ejector spring 42 of generally L-shaped configuration such as can be seen in Figures 1 and 2. As is shown in Figure 3, the ejector 42 is slightly less in width than the socket channel 43 and is secured at its central portion to the floor of the channel by a rivet 75. The inner end 47 of the ejector is bifurcated as indicated in dotted outline in Figure 3 to provide clearance between the arms thereof through which the central terminal 34 of bulb 17 can pass without contacting ejector 42. This spacing between the arms of ejector end 47 is slightly less than the diameter of the base 32 of bulb 17 so that said arms will engage the inwardly rolled rear end 33 of bulb base 32.

The reason for this arrangement will be apparent from an examination of Figure 1. It will be seen that the end 33 of the seated bulb 17 has depressed the bifurcated inner end 47 of ejector 42. Thus, both ejector 42 and battery contact spring 41 at all times urge bulb 17 out of socket 16. So long as the bulb envelope 36 and lens 12 remain intact, bulb 17 will be held in seated position by lens spring 18 which is stronger than the combined force of ejector 42 and battery contact spring 41. When either lens 12 or bulb envelope 36 is broken lens spring 18 no longer holds bulb 17 seated in socket 16 so that the bulb is then thrust out of the socket by ejector 42 and battery contact spring 41, as in Figure 2, to electrically disconnect the bulb from batteries 14.

The outer end 48 of ejector spring 42 extends through an opening 49 formed in the wall of shell 13. This outer end 48 is normally disposed in the position shown

in Figure 1 wherein switch 20 is shown in open position. When the switch 20 is closed by depression of its forward end into contact with outer end 48 the circuit is closed to seated bulb 17.

The switch means 20 includes a switch frame 50 which may be secured to the shell 13 in any desired manner. In its opposed side walls the frame 50 has two pairs of oppositely disposed apertures 51 and 52 such as are indicated in dotted outline in Figures 1 and 2. Positioned in the frame 50 are a forwardly disposed lever 53 and a rearwardly disposed trigger 54. The lever 53 has spaced apart downwardly extending side walls which are formed with oppositely disposed outstruck trunnions 55 adapted to be positioned in the pair of apertures 51. The trigger 54, like lever 53, also includes spaced side walls having trunnions 56 formed thereon adapted to be held in the frame apertures 52.

In the open position of switch means 20, the forward end of the trigger 54 overlies the rear end of the lever 53 as is shown in Figure 1. A flat spring 57 is disposed in the switch frame 50 below lever 53 and trigger 54, and includes upturned end portions one of which engages the forward portion of the lever 53 and the other of which engages the rearward portion of the trigger 54 and retains the lever and trigger in open position.

These switch means 20 are substantially identical to the switch disclosed in my United States Patent No. 2,176,084 and are fully described therein. It will be apparent that when the forward end of lever 53 is depressed, it comes into contact with the outer end 48 of the ejector contact spring 42. As is clearly set forth in said patent, the switch means 20 may be selectively locked in closed position by fully depressing the forward end of the lever 53 in order to snap the rear end of lever 53 above the forward end of trigger 54. In order to release the switch from closed position, the trigger 54 is depressed to return the several parts to the position shown in Figure 1.

The outer casing 11 is preferably made of a flexible rubber material or a synthetic such as neoprene. Casing 11 is substantially cylindrical and is closed at one end by an integral wall 58. As is shown in Figure 1, the end wall 58 is spaced inwardly to provide a recess 59 adapted to receive a carrying ring 60 which is carried by a boss 61. It will be observed that ring 60 can be folded into the recess 59 so that no part of it protrudes outwardly of the casing 11. With this construction even though the flashlight 10 is dropped, if the ring has been placed in this secure position there will be no danger of the metal ring coming into contact with other metal in order to strike a spark.

At its front end the outer casing 11 is formed with an integral enlarged portion 62 which is adapted to receive the switch means 20. The enlarged portion 62 is formed with a forwardly disposed depression 63 positioned over the lever 53 and at its rear end is formed with a depression 64 positioned over the trigger 54. Thus, when the inner shell 13 is placed inside the outer casing 11 the switch means 20 can be actuated by pressure exerted on the depressions 63 and 64 which are relatively thin-walled.

The forward end of the casing 11 is formed with an internal annular groove 65 which is adapted to receive the beaded periphery of lens 12. Thus after batteries 14 have been placed in the inner shell 13 it is then slipped into the casing 11. The bulb 17 is then placed in position in the socket 16 after which the open end of the casing can be deformed to force the lens 12 into position in groove 65. After the lens 12 is in place, the lens spring 18 at its inner end contacts bulb 17 to seat it in the socket 16. When bulb 17 is thus seated by the compressed spring 18, its central terminal 34 will depress the resilient finger 44 of the battery contact spring 41. At the same time the inwardly rolled end 33 of the bulb

base 32 will depress the resilient bifurcated end 47 of the ejector contact spring 42. Bulb 17 is thus electrically connected to the batteries 14.

The operation of the invention is extremely simple. After the flashlight 10 has been assembled in the afore-described manner it may be turned on and off merely by depressing the depressions 63 and 64, respectively. Assuming the flashlight to be "on," in the event that the envelope 36 of bulb 17 should break, the bulb 17 is at once thrust outwardly of socket 16 by the action of ejector 42 and battery contact spring 41. Both terminals of the bulb 17 are thus taken out of contact with the contact springs 41 and 42 in the manner shown in Figure 2. Accordingly, even if the filament 35 should remain intact it will no longer glow or if the filament 35 is broken no arcing across protruding ends thereof will take place since the bulb 17 is no longer electrically connected to the batteries 14. The same result will follow if lens 12 is broken.

While there has been shown herein what is considered to be the preferred embodiment of the present invention, it will be apparent that various modifications and changes may be made with respect to the foregoing description without departing from the spirit of the invention or the scope of the following claims.

I claim:

1. In a flashlight the combination of: a bulb socket made of insulating material; spring means extending between the lens of said flashlight and the envelope of a bulb to seat said bulb in said socket; a battery contact spring mounted on said socket that yields to contact therewith of one terminal of said seated bulb and is engageable by one terminal of a battery placed in said flashlight; an ejector contact spring mounted on said socket that yieldably engages the other terminal of said bulb, said battery contact spring and ejector contact spring together serving to electrically connect said bulb to battery, upon fracture of the envelope of said bulb together causing said bulb terminals to be moved out of contact with said battery contact spring and ejector contact spring.

2. In a flashlight the combination of: a metal shell adapted to enclose at least one battery; a bulb socket made of an insulating material rigidly affixed to one end of said shell adjacent to the lens of said flashlight and adapted to axially movably receive the base of a light bulb that is seated therein; a battery contact spring mounted on said socket that resiliently yields to insertion of said bulb into said socket and comprises the electrical connection of one terminal of said battery to one terminal of said bulb; a bulb ejector contact spring mounted on said socket that resiliently yields to insertion of said bulb into said socket and adapted to comprise the electrical connection of the other terminal of said bulb to a switch means of which said ejector spring is a part; and a compression spring extending between the lens of said flashlight and the envelope of said bulb to seat said bulb in said socket and to hold the terminals of said bulb in contact with said ejector spring and battery contact spring whereby said bulb is electrically connected to said battery in such a way that when said lens or the envelope of said bulb is broken said ejector spring and battery contact spring move said bulb away from said contact springs and outwardly from said socket to break said electrical connections.

3. In a flashlight for use with a bulb having a smooth cylindrical base that is outwardly flanged at its junction with the envelope of said bulb, the combination including: a substantially tubular metal shell that is adapted to enclose at least one battery; a bulb socket made of an insulating material fastened to the front end of said shell adjacent to the lens of said flashlight, said socket having an axial bore therethrough adapted to have the base of said bulb inserted therein, said bore being spot-faced at its forward end to provide a seat for the flange of said bulb base; a battery contact spring on the inner end

of said socket having a resilient finger portion adapted for yieldable engagement with the centrally disposed terminal of said bulb; an ejector contact spring on the inner end of said socket having a bifurcated inner end portion adapted to yieldably engage peripheral rear end portions of the base of said bulb, said portions constituting the other terminal of said bulb; switch means on said shell including said ejector spring that on closing engage the outer end of said ejector spring; and a spring on the center of the inner face of a lens of said flashlight that compressively engages the envelope of said bulb to seat it in said socket for electrical connection to batteries in said flashlight through said contact springs so that upon fracture of said lens or bulb envelope the base of said bulb is thrust outwardly by said ejector spring and battery contact member whereby to break said electrical connection.

4. A device as set forth in claim 3 in which the lens is held in one end of a rubber-like outer casing, said lens and casing together providing a fluid-sealed housing for said flashlight.

5. In a flashlight for use with a bulb having a smooth cylindrical base that is outwardly flanged at its junction with the envelope of said bulb, the combination including: a fluid-sealed housing for said flashlight comprising a tubular casing of an impervious rubber-like material closed at the rear end by an integrally formed wall and a lens set in fluid-sealing engagement in the front end of said casing; a substantially tubular metal shell adapted to be slideably received in said casing for enclosing at least one battery; a bulb socket made of an insulating material fastened to the front end of said shell adjacent said lens, said socket having an axial bore therethrough adapted to have the base of said bulb inserted therein, said bore being spot faced at its forward end to provide a seat for the flange of said bulb base; a battery contact member fastened in diametrically extending position across the rear end of said socket and over said axial bore and formed with a central rearwardly extending dimple for electrical contact with a center terminal of said battery and having a forwardly and reversely folded resilient finger portion adapted for yieldable contact with a centrally disposed terminal of said bulb; an ejector contact spring on the inner end of said socket having a bifurcated inner end portion intercepting said axial bore and adapted to yieldably engage peripheral rear end portions of said bulb, said portions constituting the other terminal of said bulb, the outer end portion of said ejector contact spring protruding outwardly through said metal shell for switching engagement with a manual switch mounted on said shell, said switch being depressible through a side wall portion of said casing to electrically close against the outer end of said ejector spring to complete a circuit comprising said battery, said shell, said battery contact member, said ejector spring, and said bulb; and a spring on the center of the inner face of said lens that compressively engages the envelope of said bulb to seat said bulb in said socket for electrical connection to said batteries through said contact springs so that upon fracture of said lens or bulb envelope, the base of said bulb is thrust outwardly of said socket by said ejector spring and battery contact member and away from said ejector spring and battery contact member whereby to break from said ejector spring and battery contact member whereby to break said electrical connection to avoid ignition of materials entering said flashlight after such fracture.

6. In a flashlight including a lens, a switch means, a socket of an insulating material adapted to axially movably receive the base of a bulb seated in said socket, and a means between said bulb and lens yieldably urging said bulb into a seated position in said socket, the improvement comprising the combination of: a resilient battery contact means on said socket between one terminal of said battery and one terminal of said bulb to electrically

interconnect them; and a resilient switch contact means mounted on said socket and operatively associated with a switch means and adapted to electrically interconnect said switch means and another terminal of said bulb, both said contact means being adapted to oppose the force of said yieldable means to thrust said bulb out of said socket only upon fracture of said bulb or said lens.

7. In a flashlight including a lens, a switch means, a socket of an insulating material adapted to axially movably receive the base of a bulb seated in said socket, and a means between said bulb and lens yieldably urging said bulb into a seated position in said socket, the improvement comprising the combination of: a unitary means mounted on said socket that is made of a resiliently deformable material and is yieldably engageable by one terminal of said bulb and is adapted to comprise the sole electrical connection between said one bulb terminal and a terminal of a battery receivable in said flashlight; and a unitary means mounted on said socket that is made of a resiliently deformable material and is yieldably engageable by the other terminal of said bulb and is adapted to comprise the sole electrical connection between said other bulb terminal and a switch means of said flashlight, both said unitary means being adapted to oppose said yieldable means to thrust said bulb out of said socket only upon fracture of said bulb or of said lens.

8. In a flashlight including a lens, a switch means, a socket adapted to axially movably receive the base of a bulb seated in said socket, and a means between said bulb and said lens yieldably urging said bulb into a seated position in said socket, the improvement comprising the combination of: a spring member of a conducting material mounted on said socket and having a portion depressible by one terminal of said bulb and another portion in contact with one terminal of a battery receivable in said flashlight to electrically connect said battery and said one bulb terminal; a second spring member of a conducting material mounted on said socket and insulated from said first member and having a portion depressible by the other terminal of said bulb, said second member being adapted to electrically connect said other bulb terminal to a switch means of which said second member is a part, both said members being adapted to oppose said yieldable means to thrust said bulb out of said socket only upon fracture of said bulb or said lens.

9. In a flashlight for use with a bulb having a smooth,

5 cylindrical base and including a lens, a switch means, and a spring means on said lens adapted to yieldably urge said bulb into a seated position in a socket of said flashlight, the improvement comprising the combination of: a bulb socket made of an insulating material that has an axial bore therethrough adapted to axially, slideably receive and to seat the base of said bulb; a battery contact member fastened in diametrically extending position on said socket over the rear end of said axial bore and having a portion adapted for electrical contact with one terminal of a battery in said flashlight and having a forwardly and reversely folded resilient finger portion adapted for yieldable contact with a centrally disposed terminal of said bulb, said battery contact member comprising the sole electrical connection between said central terminal of said bulb and said battery; an ejector contact spring fastened to said socket formed with a bifurcated inner end portion intercepting said axial bore of said socket that is adapted to yieldably engage peripheral rear end portions of said bulb, which portions constitute the other terminal of said bulb, the outer end of said ejector contact spring comprising a portion of a switch means for said flashlight and said ejector contact spring comprising the sole electrical connection between said other terminal of said bulb and said switch means, both said springs being adapted to oppose said spring means for yieldably urging said bulb into seated position and adapted to both thrust said bulb out of said bore of said socket only upon fracture of said bulb or of said lens.
